UMBRELLA

Fritz Rosenberg, Brooklyn, N. Y., and Wayne S. Evans and John Lutz, Philadelphia, Pa.; said Evans and Lutz assignors to said Rosenberg

Application March 29, 1937, Serial No. 133,720

7 Claims. (Cl. 135—29)

The object of this invention is to provide improvements in umbrellas broadly, but more particularly in reversible types of umbrella frames.

Another and more specific object is to provide an improved umbrella frame, which is adapted to be reversed, either wholly or only partially, as by the action of a high wind, and which frame when only partially reversed returns automatically to its normal shape or position, and in addition to provide a construction in which each rib unit is flexible and reversible, independently of the other units (except as they are connected together by the usual cover), with the result that one side alone can flex without materially disturbing the opposite side, as when a light wind strikes the umbrella from an angle, instead of from directly beneath.

Still another object is to provide in one form of the improved frame a sectional stretcher, connecting the usual sleeve, which is slidable upon the shaft, to a given rib, and resilient means automatically tending to maintain a predetermined relationship between such stretcher and rib, whereby when the umbrella is in extended position the stretcher imposes its frame-expanding force directly upon the rib, but is adapted in emergencies to have its effective length extended sufficient to permit such rib to oscillate into a reversed position.

A further object is to provide the resilient means in such a structure in the form of a preferably spiral spring, located at the pivotal connection between the rib and the adjacent stretcher section or link, although such resilient means in the same or different form may be located at the pivotal connection between the stretcher sections themselves, or possibly elsewhere as may be feasible and desired.

And a still further object is to provide a modified form of umbrella frame in which a suitable sliding connection is interposed between a single-section stretcher and the rib, so as to permit the rib to oscillate into reversed position, as herein-after described.

With the objects of the invention thus briefly stated, the invention comprises further details of construction and operation, which are fully brought out in the following description, when read in conjunction with the accompanying drawing, in which Fig. 1 is a side elevation of an umbrella, the top thereof, when in reversed position, being indicated by dot-and-dash lines; Fig. 2 is an enlarged detailed side elevational view of the major portion of one of the ribs of said umbrella, together with the adjacent portions of the im-

proved sectional stretcher, said stretcher being shown in normal operative position in full lines, and in inoperative position in dot-and-dash lines; Fig. 3 is a bottom plan view of said rib, together with the adjacent link section of the stretcher in normal operative position; Fig. 4 is a longitudinal central section, the same showing the link section of said stretcher attached to the adjacent portion of the main section of same; Fig. 5 is a fragmentary side elevation of a rib and the adjacent portion of a stretcher, comprising a modified form of the invention; Figs. 6 and 7 are sections on the lines 6—6 and 7—7 respectively of Fig. 5.

Referring to Figs. 1, 2, 3 and 4 of the drawing, an umbrella is shown as comprising a shaft 1, upon which is mounted in the usual manner a flexible cover 2, supported by radially extending, angularly spaced ribs 3, which in this instance are of the usual U-shaped cross section and are provided at their inner ends with apertures 4 for the reception of suitable means for hingedly attaching them to said shaft.

Each of said ribs is provided at an intermediate point with a fixedly positioned lug 5, having spaced ears 6, to which is attached by suitable pivot pin 7 a relatively short stretcher section 8, the free end portion 9 of which is adapted to enter within the concave side of the rib 3 and normally cooperate therewith in positive contact. To a suitable intermediate portion of said link section is pivotally secured, by means of a pin 10, the outer free end portion of the main stretcher section 11, the opposite or inner end of said main stretcher section being pivotally secured to the usual sleeve (not shown), which customarily slides upon the shaft 1. It will also be noted that a coil spring 12 surrounds the pin 7 and comprises oppositely extending terminal portions 13 and 14, which respectively cooperate directly with the inner concave surface of the rib 3 and the link section 8 of said stretcher, for the purpose of maintaining said stretcher section in the operative position herein described and illustrated.

In the operation of an umbrella constructed in accordance with this invention, the several ribs are "raised" into their extended positions, as shown in Fig. 1 and as indicated also in Fig. 2, wherein the main stretcher section 11 presses directly outwardly and upwardly against the corresponding rib by virtue of the intervening free end portion 9 of the link section 8, and the direct cooperation thereof with said rib. However, when a gust of wind, or other unusual force, re-

verses the position of the ribs and cover, either partially or entirely so, as indicated by the dot-and-dash lines 15, the effective length of each stretcher is increased for as the rib moves upwardly in the direction of the arrow 16, the stretcher pivot 10 moves in an arc, as indicated by the arrows 17, so that said stretcher sections pass through intermediate position, as indicated by the dot-and-dash position 18, until they reach the dot-and-dash position 19, which by design is sufficient to permit a full reversal of the umbrella frame, as mentioned, thereafter pulling simultaneously downwardly upon the several main rib sections 11, through the medium of the usual sleeve surrounding the shaft 1, which operates to pull the several ribs back into normal extended position, and as they pass a plane perpendicular to said shaft at the pivotal mountings 4, the tension upon said stretcher sections is immediately relieved, whereupon the spring 12 operates to force the adjacent stretcher link section into the normal operative position, hereinbefore described, which position is retained, even as the umbrella frame is "lowered" or collapsed in the usual manner by sliding downwardly the shaft-surrounding sleeve, to which the inner ends of said stretcher sections are pivotally connected. A frame of this type provides a construction in which each rib unit is flexible and reversible, independently of the other units (except as they are connected together by the usual cover), with the result that one side alone can flex without materially disturbing the opposite side, as when a light wind strikes the umbrella from an angle, instead of from directly beneath.

Referring to Figs. 5, 6 and 7, there is here shown a rib 20, upon which is slidably mounted a lug 21 having spaced ears 22, to which is pivotally secured at 23 a single-section stretcher 24. In this case, as an unusual force tends to partially or wholly reverse the umbrella frame, the lug 21 slides along said rib into the dot-and-dash position indicated at 25, the two extreme positions of said lug being limited by stops 26 and 27, suitably secured to said rib. Otherwise the operation of this modified form of the device provides for an operation of the umbrella frame as a whole in a manner similar to that hereinbefore described.

Having thus described our invention, what we claim as new and desire to protect by Letters Patent of the United States is as follows:

1. An umbrella frame, comprising a rib and a stretcher, said stretcher in turn comprising a main section and a link section, pivotally connected to said main section and to said rib, the outward thrust upon said stretcher operating to normally maintain said link section substantially parallel with said rib and the outward thrust of said stretcher in effect directly against said rib.

2. An umbrella frame, comprising a rib, a

stretcher, said stretcher in turn comprising a main section and a link section, pivotally connected to said main section and to said rib, and resilient means to normally maintain said link section in proximity to, and said main section in substantially direct contact with, said rib.

3. An umbrella frame, comprising a rib, and a sectional stretcher, said stretcher in turn comprising a main section and a link section, said link section being pivotally connected at one end 10 to said rib, and pivotally connected also to said main section, beyond which last-named connection said link section freely extends in a projection, said projection in one position contacting with a portion of said rib spaced from 15 said first connection, to transmit force from said main section substantially directly to said rib.

4. An umbrella frame, comprising a rib, a sectional stretcher, said stretcher in turn comprising a main section and a link section, said link 20 section being pivotally connected at one end to said rib, and pivotally connected also to said main section, beyond which last-named connection said link section freely extends, and is adapted in one position to contact with a portion 25 of said rib spaced from said first connection, to transmit force from said main section substantially directly to said rib, and resilient means to normally maintain the link section of said stretcher closely adjacent to said rib.

5. An umbrella frame, comprising a shaft, a rib pivotally connected to said shaft, a sectional stretcher in turn comprising a main section, at one end pivotally connected to and in slidable engagement with said shaft, and a link section 35 pivotally connected to the opposite end portion of said main section and also to said rib, and resilient means to normally maintain said sections out of alignment, and said link section in close proximity to said main section.

6. An umbrella frame, comprising a shaft, a rib pivotally connected to said shaft, a sectional stretcher in turn comprising a main section, at one end pivotally connected to and in slidable engagement with said shaft, and a link section 45 pivotally connected to the opposite end portion of said main section and also to said rib, and resilient means to normally maintain said sections out of alignment, and said link section in close proximity to said main section, but operative to permit said rib to oscillate into reversed position 50 with respect to said shaft by increasing the effective length of said stretcher.

7. An umbrella frame, comprising a rib and a sectional stretcher, connected to said rib and operative to permit said rib to assume a reversed position, and also operative to return said rib 55 from reversed to normal operative position.
